ECCLESIASTICAL VOTIVE STAND

Frank D. Oesterle, West Englewood, N. J.

Application September 13, 1954, Serial No. 32,268

Term of patent 14 years

(Cl. D29—23)

To all whom it may concern:

Be it known that I, Frank D. Oesterle, a citizen of the United States, residing at West Englewood, in the county of Bergen and State of New Jersey, have invented a new, original, and ornamental Design for an Ecclesiastical Votive Stand, of which the following is a specification, reference being had to the accompanying drawing, forming part thereof.

In the drawing:

Figure 1 is a front elevational view of an ecclesiastical votive stand showing my new design, rows of candle holding cups being shown in broken lines;

Figure 2 is a side elevational view thereof with portions broken away for the convenience of illustration;

Figure 3 is a rear elevational view thereof with por-

tions broken away for convenience of illustration only; and

Figure 4 is a top plan view thereof.

The dominant features of my design reside in those portions shown in full lines.

I claim:

The ornamental design for an ecclesiastical votive stand, substantially as shown and described.
